UNITED STATES PATENT OFFICE.

PIERRE MARIE GABRIEL TOULON, OF PARIS, FRANCE, ASSIGNOR, BY MESNE ASSIGNMENTS, TO GENERAL ELECTRIC COMPANY, A CORPORATION OF NEW YORK.

DEVICE FOR CONTROLLING THE CURRENT PRODUCED BY VAPOR RECTIFIERS.

Original application filed May 22, 1925, Serial No. 32,226, and in France May 27, 1924. Divided and this application filed October 27, 1926. Serial No. 144,623.

My invention relates to means for making use of vapor rectifiers such as those disclosed in my United States Patent applications 682,093 and 682,099 for producing optic signals corresponding to telephonic signals impressed on the control arrangement of the rectifier. In the above mentioned applications this control arrangement consists in a metallic coating surrounding the rectifier and the potential of which prevents, when it is brought above a given value, the arc from forming in the rectifier before a given moment of the half period during which it is normally ignited.

According to my invention, the primary circuit transmitting the sounds acts on the potential of the said coating in view of making the intensity of the light given out by the arc vary accordingly.

This invention is a division of application Ser. No. 32,226 filed on May 22, 1925.

In the appended drawings Fig. 1 shows by way of example, a device transforming electric telephone signals into optic signals.

Figs. 2 to 5 are explanatory diagrams.

Fig. 1 gives the electric connections used with an arc rectifier for optically transmitting radio-telephonic signals and if desired for registering them.

The apparatus as shown allows a modulation that is, a series of changes very close together in the rectified current, according to the potential of the grid of an ionic valve connected with the rectifier acting as a relay.

The progressive variation of the rectified current is caused (see Fig. 2) by modifying the phase of the alternating current feeding the coating or outer grid of the rectifier the frequency of which is equal to that of the

current feeding the anode. The difference of potential between the anode and the cathode being shown by the curve 27 and that between the coating and the cathode by the curve 28, the arc will be ignited when the

latter difference of potential is positive and greater than the value obtained at 29. A current the intensity of which is shown by the curve 32 passes during the interval 30—31.

The phase displacement between the potentials of the anode and of the coating can be controlled at will as hereinafter set forth.

Fig. 3 shows the phase of the difference of potential between the anode and the cathode.

Two different phases of the difference of potential between the coating and the cathode are shown in O A and O B. Each of these can be obtained by combining the anode-cathode difference of potential O X and a variable difference of potential X A or X B. The phase-displacement of the resultant alternating difference of potential *a* or *b* would be caused only by the value of the vector X A or X B.

Therefore for altering progressively the phase of the potential of the coating, it is sufficient to add a potential the alternating phase of which is constantly in opposition with that of the anode and an alternating potential of variable amplitude making a phase angle of 90° with the potential of the anode. Fig. 4 shows the curve corresponding to the current passing through the rectifier. Fig. 5 shows the curve corresponding to the same current after it has passed through a number of induction coils.

The two component potentials are produced in secondary windings of a transformer the primary winding whereof is fed by the same supply as the arc itself. The current the potential of which is opposed to that of the anode is obtained simply by closing the circuit of one of the secondary windings over a resistance devoid of self induction. The second current the potential of which is at 90° to the preceding one is produced in another winding of the transformer which is closed through a large induction coil and a resistance connected in series, the current to the coating being branched at the extremity of the said resistance.

The value of the current opposed to the potential of the cathode is constant whereas that of the second current is variable. In view of this the ionic valve through which passes the current to the coating is connected in series with a resistance the value of which is equal to the mean value of the resistance of the interval filament-plate. A potentiometer in parallel with the lamp and the resistance allows an adjustment of the potential.

When the potential of the grid in the electron valve varies, the current in the plate changes, the fall of potential in the resistance in series with the lamp changes, whereby the value of the alternating current at 90° with the feeding current of the recti-

fer anode changes correspondingly. This causes a phase-displacement in the potential of the coating and consequently, a corresponding variation in the value of the rectified current.

This arrangement allows thus the value of the rectified current to be controlled at every moment. It is therefore very useful for amplifying any inflexion in the value of the current passing through the ionic valve. Thus it can be used in numerous cases such as for the exact adjustment according to the temperature in a cold-producing plant of the speed of an electric motor which drives said plant; a thermo-electric couple acts upon the grid of the lamp and the current rectified by the rectifier feeds the electric motor. This permanent adjustment is far superior to the methods actually used according to which the regulative means become operative only when a certain temperature is reached.

Returning to the description of Figure 1, the microphone 1 fed by the battery 2 is connected in series with the primary of a telephonic transformer 3, the secondary of which feeds the grid 4 of an electron valve.

The filament 5 is suitably heated, by the battery of accumulators 5' for instance. The plate 6 is connected in series with a resistance 7.

A silent generator of alternating current of comparatively high frequency is connected across terminals 8 and feeds the primary of a transformer 9. One of the secondary windings 9' of this transformer feeds the anode 10 of the mercury lamp 11 through the resistance 12. A second secondary winding 9'' of the transformer 9 supplies the potential of the plate of the electron valve; it feeds therefore a resistance 13 through an induction coil 13' which displaces the phase of the current substantially 90° with reference to the potential of the current feeding the mercury lamp.

A third winding 9''' of the transformer 9 feeds a resistance 14 and affords a current the potential of which is opposed to that of the anode. The resistances 7 and 14 are connected in series and their extremities are connected on one side to the cathode and on the other to the coating of the mercury lamp. The connections described hereinbefore produce a potential in the coating the phase displacement of which, with reference to the anode, varies in accordance with the value of the acoustic waves reaching the microphone.

As explained hereinbefore, a phase-displacement of the potential of the coating with reference to that of the anode limits for each period of the alternating current feeding the rectifier the time during which the rectified current is allowed to pass.

This time is a given fraction of the period, so that the mean current passing through the lamp and the mean brilliancy of the arc vary correspondingly with this time of allowed passage.

The above described connections cause the brilliancy of the arc to vary with the phase displacement of the potential of the coating and therefore with the intensity of the acoustic waves reaching the microphone.

In other words an acoustic wave makes the microphone wave alter which changes the potential of the grid 4. This in its turn causes a difference of potential between the points A and B and thereby a phase-displacement of the potential of the coating.

In order to increase the brilliancy of the arc, without producing an exaggerated heating of the whole of the tube which would prevent a proper working of the coating and a proper inspection of the brilliancy of the arc, it is preferable to provide the lamp with a narrow part along the axis of said lamp and in the direction which is to be lightened. The luminous rays can be projected by a lens 15 or by a suitable mirror.

In order to ensure secrecy to the optic signals, the visible part of the spectrum of the rays produced can be eliminated by a suitable screen 16 which only lets either the ultraviolet or the ultra-red rays pass.

The optically transmitted signals can be received directly by the eye or by means of an optical device or else be registered on a photographic film.

What I claim is:

1. In combination with an arc lamp provided with an outer control grid fed by an alternating current of the same frequency as the feeding current of the lamp, means for making the phase-displacement of the said grid with reference to the feeding current follow any desired inflexions, these variations of the phase displacement occurring even at intervals smaller than the period of the currents, whereby the intensity of the rectified current produced by the arc lamp follows the said inflexions.

2. In combination with an arc lamp provided with an outer control grid fed by an alternating current of the same frequency as the feeding current of the lamp, means for feeding the control grid with a current in opposition with the feeding current and with a second current of variable amplitude according to the inflexions which it is desired to impress on the phase-displacement of the resultant current feeding the control grid, the said second current being phase-displaced by 90° with reference to the feeding current.

3. In combination with an arc lamp provided with an outer control grid fed by an alternating current of the same frequency

- as the feeding current of the lamp, means
for feeding the control grid with a current
in opposition with the feeding current and
with a second current phase-displaced by
5 90° with reference to the feeding current and
the amplitude of the voltage of which is
controlled by the plate of an ionic valve the
grid of which receives the current whereof
10 the variations are caused by the inflexions
which it is desired to impress on the phase-
displacement of the resultant current feed-
ing the control grid of the lamp.
4. The combination of a vapor electric de-
vice provided with a cathode and an anode
15 enclosed within an evacuated vessel and with
a grid, means arranged to apply alternating
current potentials between said cathode and
said anode and between said cathode and
said grid, a sound responsive device, and
20 means arranged to vary the phase relation
between the potentials of said grid and anode
in accordance with the operation of said
sound responsive device.
5. The combination of a vapor electric de-
25 vice provided with a cathode and an anode
- enclosed with an evacuated vessel and with
a grid, means arranged to apply alternating
current potentials between said cathode and
said anode and between said cathode and
said grid, a sound responsive device, and 30
means comprising an electron valve arranged
to vary the phase relation between the po-
tentials of said grid and anode in accordance
with the operation of said sound responsive
35 device.
6. The combination of a vapor electric de-
vice provided with a cathode and an anode
enclosed within an evacuated vessel and with
a grid, means arranged to apply alternating
current potentials between said cathode and 40
said anode and between said cathode and
said grid, means for producing electrical
impulses, and means comprising an electron
valve arranged to vary the phase relation
between the potentials of said grid and anode 45
in accordance with said impulses.

In testimony whereof I have affixed my
signature.

PIERRE MARIE GABRIEL TOULON.
